(57) CLAIM

The ornamental design for a table, as shown and described.

DESCRIPTION

FIG. 1 is a top front perspective view of a table, showing my new design;

FIG. 2 shows a front view of the table of FIG. 1;

FIG. 3 shows a rear view of the table of FIG. 1;

FIG. 4 shows a top view of the table of FIG. 1;

FIG. 5 shows a left side view of the table of FIG. 1, the right side being a mirror image thereof.

FIG. 6 is a top front perspective view, showing a second embodiment of our new design;

FIG. 7 shows a front view of the table of FIG. 6;

FIG. 8 shows a rear view of the table of FIG. 6;

FIG. 9 shows a top view of the table of FIG. 6; and,

FIG. 10 shows a left side view of the table of FIG. 6, the right side being a mirror image thereof.

The dashed-line showing of environment in the various figures is for illustrative purposes only and forms no part of the claimed design.
